CLAIM

The ornamental design for covered ice cube tray, as shown and described.

DESCRIPTION

FIG. 1 is a perspective view of a covered ice cube tray, showing my new design, with one of the lids removed for clarity of illustration;

FIG. 2 is a top view thereof;

FIG. 3 is a side view thereof, the other side being identical;

FIG. 4 is a bottom view thereof;

FIG. 5 is an end view thereof, the other side being identical;

FIG. 6 is a fragmentary sectional view thereof, taken in the direction of the arrows on line 6—6.

FIG. 2

FIG. 3

FIG. 4

FIG. 6

FIG. 5
